US00D824608S

(12) **United States Design Patent** (10) Patent No.: **US D824,608 S**
(45) Date of Patent: ** Jul. 31, 2018

(54) **TOPLOAD WASHING APPLIANCE**

(71) Applicant: **WHIRLPOOL CORPORATION**,
Benton Harbor, MI (US)

(72) Inventors: **Seth E. Bixby**, Stevensville, MI (US);
Richard K. Gresens, Saint Joseph, MI
(US); **John W. McConnell**, Saint
Joseph, MI (US); **Patrick J. Schiavone**,
Benton Harbor, MI (US); **Samuel B.
Breneman**, Saint Joseph, MI (US)

(73) Assignee: **Whirlpool Corporation**, Benton
Harbor, MI (US)

(**) Term: **15 Years**

(21) Appl. No.: **29/607,502**

(22) Filed: **Jun. 14, 2017**

CLAIM

We claim the ornamental design for a topload washing
appliance, as shown.

DESCRIPTION

FIG. 1 is a first top perspective view of the topload washing
appliance of the present invention;

FIG. 2 is a second top perspective view of the topload
washing appliance of the present invention;

FIG. 3 is a top plan view of the topload washing appliance
of the present invention;

FIG. 4 is a bottom plan view of the topload washing
appliance of the present invention;

FIG. 5 is a first side elevation view of the topload washing
appliance of the present invention;

FIG. 6 is a second side elevation view of the topload washing
appliance of the present invention;

FIG. 7 is a third side elevation view of the topload washing
appliance of the present invention; and,

FIG. 8 is a fourth side elevation view of the topload washing
appliance of an alternative embodiment of the present invention.

The broken lines in the figures are for contextual purposes
or show the environment and form no part of the claimed
design.
